HEAT INTENSIFIER FOR BOILERS

Application filed May 11, 1928. Serial No. 277,019.

This invention relates to combustion devices according to which heated air is supplied over the head of fuel in boilers, furnaces and the like in order to oxidize combustible gases in the firebox and thus generate more heat. Many different kinds of such devices have been suggested heretofore and are being used.

The heating unit of such devices must extend substantially deeply into the firebox in order to become heated to the high degree desired, namely, substantially to redness. Usually the unit becomes at least a cherry red when the fire is burning with ordinary intensity for heating purposes, and reaches an almost white heat under some conditions. One serious difficulty in the art has been to devise a heating unit that would stand the effects of the high temperatures and the fluctuations in temperatures encountered, and another has been to provide a high degree of efficiency especially at some of the lower temperatures, as when the fuel bed is burning at a relatively low rate and at which time the processes of distillation release valuable combustible gases which unless promptly oxidized are lost through the flue stack. The prime objects of the present invention are to improve the results in the directions just mentioned. Other objects and advantages will appear hereinafter.

In the drawings which form a part hereof

Figure 1 is a top plan view of our device as applied to a boiler.

Figure 2 is a section along the line 2—2 of Figure 1.

Figures 3 and 4 are detail views of portions of our device, and

Figure 5 is a diagrammatic view of a boiler embodying the device.

In carrying out our invention, we provide a unit 1 which is composed of an outer casing 2 and an inner casing 3. The inner casing 3 is made integral with the outer casing 2 through tubular connecting portions 4 and 5. Passageways 6 and 7 are provided in the portions 4 and 5, respectively, thus providing communication with the interior of the casing 3 which may be termed as a compartment 8.

An air chamber 9 is provided in the outer casing 2 around the inner casing 3. An inlet opening 10 is provided for the air chamber 9. A mouth portion 11 is provided integral with the outer casing 2 and is provided with a relatively narrow horizontally extending outlet opening 12. The ends of the outlet opening 12 taper or flare outwardly.

The outer casing is provided with equally spaced ribbed portions 13 which extend from the passageways 6 and 7 about the outer periphery of the outer casing. The inner wall of the outer casing is provided with trough-like recesses 14 positioned radially opposite the ribbed portions 13 respectively and extending in the same general direction.

The unit 1 is provided with a flange 15 which extends outwardly from the outer casing 2 about the inlet opening 10 and is rectangular in general contour.

A supporting member or frame 16 is provided with a substantially U-shaped retaining portion 17. The portion 17 is provided with inwardly extending projections 18 overlying flanges 15 at the sides. An opening 19 is provided in the frame 16 in alignment with the inlet opening 10 of the unit 1. Side walls 20 and end walls 21 are provided for the frame 16 and are arranged to be disposed adjacent to a door 22 of a boiler 23 and secured in place by means of bolts 24 or the like.

From the foregoing description of the various parts of the device, the operation thereof may be readily understood. When the frame 16 is secured in place adjacent to the inner wall of the door 22, the group of inlet passageways 25 in the door is completely surrounded, whereby air entering the boiler through the air passageways 25 must pass through the opening 19.

The unit 1 may be secured to the frame 16 so that the outlet opening 12 is substantially in a horizontal plane with respect to the opening 19. To secure the unit 1 to the frame 16 in this position, a straight key 26, see Figure 3, is disposed upon each side of the unit between the flange 15 and the inwardly extending projections 18.

When the unit 1 is in this position, the air

as it enters through the openings 25 will pass through the opening 19 and into the air chamber 9. Let us assume that there is a fire in the boiler. The heat from the fire within 5 the boiler will heat the outer casing 2, and as the heat passes through the passageways 6 and 7, the inner casing 3 will also become heated. Therefore, as the heat passes through the passageway 7, it will be received 10 in the compartment 8, therefore heating the inner casing. In this manner the inner casing may be readily heated as well as the outer casing. Therefore, as the air passes through the openings 25 and the opening 19 into the 15 chamber 9, it will become heated as it contacts with the wall of the outer and inner casings. The air in entering the chamber 9 will contact with the inner casing and pass around the inner casing to the outlet opening 12. The outlet opening 12 is elongated laterally and is substantially narrow vertically, as will be observed from the dotted lines of Figure 2. Therefore, the air as it 20 passes through the outlet opening 12 will be spread or fanned out in a generally horizontal plane over the fire in the boiler.

It is sometimes desirable to direct the air upwardly as it enters the boiler so that it will not be directed into the fire or into the bed 30 of coals. To accomplish this, the keys 26 may be removed and tapered keys, indicated at 27, may be inserted in their place.

The ribbed portions 13 provide a double function in that they not only reinforce the 35 outer casing so as to prevent breakage, but they, in combination with the concaved recesses, permit the outer casing to expand properly due to the intense heat.

In Figure 5 we have shown an auxiliary 40 means for heating the air before the air comes in contact with the interior of the boiler. This auxiliary means consists in the provision of a pipe or tube 28 which has one end in communication with the steam chest 29 45 of the boiler and the other end extending through the opening 19 and in communication with the chamber 9. In this manner steam is allowed to pass into the chamber 9 so as to heat the air as it passes therethrough 50 and into the boiler. This is a valuable feature when breaking up the fire and applying fresh fire in the boiler of a morning. Thus a spray of steam and air may be spread over the fire and well-known advantages of such 55 an introduction obtained. Further advantages are had, however, over such as are ordinarily obtained in that according to these improvements in this respect the air and steam are raised to a high temperature immediately before they are discharged over the fuel bed, and also in that the air and steam vapor are commingled with each other in the device.

The outer and inner bodies 2 and 3 are 60 shown as being substantially spherical, which

is the preferred form, although other bulbous formations are within the purview of this invention. An important feature of the improvement is in making both of these bodies, together with the tubular elements or 70 devices 4 and 5, integral with each other. To this end the device is preferably a casting of gray iron, but other fire-resisting compositions may be employed in moulded form. The spherical or other bulbous form together 75 with this unitary or integral construction makes for peculiar strength and resistance to the disintegrating and otherwise destructive effects of the heat, since such a body does not break and become distorted nearly as 80 readily as does a cylindrical or rectangular shape, and is less subject to the burning away of small formations such as corners. The integral formation strengthens the construction greatly against warping and cracking, 85 and this, taken with the corrugations 13-14 provides an unusually satisfactory device in this respect. The recesses 14 are peculiarly important since the expansion strains are here given a directional outlet or relief where 90 they may expend themselves without objectionably distorting the shell or body as a whole.

A notable improvement is in the bulbous nature of the inner body 3 which provides 95 a relatively large hollow interior adapted to contain a materially large body of the heated furnace gases and to delay the passage of such gases through the device until their heat units may be to a large extent absorbed by 100 the walls of the inner body. A further important feature is in the fact that the passageway 9, substantially surrounding the inner body, is a radially shallow one, and thus a substantially thin envelope of air, or air 105 and steam, is subjected, both outside and inside the device, to the furnace heat. In other words there is an unusually large area of heating surface and an unusually shallow body of air to be heated at any given place. 110 This makes for a high and unusual degree of efficiency, and at the same time the device has unusually long life in service.

We contemplate as being included in these 115 improvements all such changes, departures and variations from what is thus specifically illustrated and described as fall within the scope of the appended claims.

We claim:

1. A combustion device of the character 120 described comprising walls forming a hollow bulbous outer body having an intake port and a discharge port substantially at opposite ends of the body respectively and having means for securing the body to a furnace 125 at an air intake opening thereof with such intake opening in communication with said intake port and with said body extending into the firebox of such boiler there being walls forming an inner hollow bulbous body 130

within and spaced from the walls of the outer body to provide a substantially shallow passageway substantially surrounding the inner body and extending between and opening into said ports respectively, there being at least two tubular devices connecting the interior of said inner body with the exterior of said outer body at widely spaced-apart intervals circumferentially of the outer body for the purpose specified.

10 2. The combustion device of claim 1 hereof in which said inner and outer bodies and said tubular devices are all integral with each other.

15 3. The combustion device of claim 1 hereof in which said inner and outer bodies are substantially spherical and are integral with each other and with said tubular devices.

20 4. The combustion device of claim 1 hereof in which the walls of said outer body are of integral formation and are corrugated for the purpose specified.

25 5. The combustion device of claim 1 hereof in which said inner and outer bodies and said tubular devices are all integral with each other and the walls of said outer body are formed with recesses extending in the same general direction for the purpose specified.

30 6. The combustion device of claim 1 hereof in which there are means for supplying live steam to said passageway between the inner and outer bulbous bodies to be discharged at said discharge port.

35 7. The combustion device of claim 1 hereof in which there are means for supplying live steam to said passageway between the inner and outer bulbous bodies and in the form of a jet directed toward the discharge port and spaced from the adjacent walls of the outer body to entrain air to be discharged with the steam at said discharge port.

40 Signed at Chicago, in the county of Cook, and State of Illinois this 7th day of May, A. D. 1928.
